FASTENING DEVICE

Oscar Vatet, Pleasantville, N. Y.

Application November 3, 1941, Serial No. 417,630

1 Claim. (Cl. 85—31)

(Granted under the act of March 3, 1883, as
amended April 30, 1928; 370 O. G. 757)

The invention described herein may be manufactured by or for and used by the Government of the United States for governmental purposes without the payment to me of any royalty thereon, in accordance with the provisions of the act of April 30, 1928 (ch. 460, 45 Stat. L. 467).

My invention relates to certain improvements in fastening devices, particularly those of the driven class, of which the following is a specification.

In the carrying out of low cost housing projects it has become desirable to use a comparatively soft, fibrous or granular sheathing of comparatively little thickness, such as fiber, plaster, or gypsum board or the like for the outer walls of the units of such projects and cover the same with an outer sheathing such as clapboard or wall shingles or the like. However, there is at present no fastening device on the market that can be driven so that it will hold such outer sheathing to this class of inner sheathing. For this purpose I have developed my improved fastening device which is illustrated in the accompanying drawing wherein like reference characters indicate like parts and wherein:

Figures 1, 2 and 3 represent one modification of my improved fastening device, Figure 1 being a perspective view thereof, Figure 2 a side elevation showing the action of the device as it enters the inner sheathing, and Figure 3 a side elevation showing the device when fully driven and its action in holding the outer sheathing to the inner sheathing.

Figures 4, 5, 6, 7 and 8 represent another modification of my improved fastening device, Figures 4 and 5 being side elevations thereof, the latter being partly in section and the former showing its action at the start of the driving operation, Figure 6, a side elevation showing the device when fully driven, and Figures 7 and 8 being plan views of the device before and after being driven.

Generally these devices consist of a head 1, and a shank 2, the outer portion of which is of sufficient length and strength to withstand the hammer blows and extend through the outer sheathing 3 and the inner portion of which is perforated axially to form a series of weaker portions which successfully break and permit the bevelled points to spread the inner portion of the shank out into the inner sheathing 4 as it is being driven, the metal surrounding the perforations forming barbs which bite into the structure of the inner sheathing and hold the

fastening device firmly in place without passing through the inner sheathing.

As illustrated in Figures 1 to 3 one form of my improved fastening device may have a series of holes 5 formed along the inner portion of the shank, i. e., near the point which is provided with an interior bevel 6, viz tapered downwardly and outwardly, there remaining between the holes 5 small sections of metal 7 which give 10 rigidity to the inner portion of the shank, preventing appreciable spreading of the shank until after it passes through the outer sheathing 3. This action is illustrated in Figure 2 wherein it will be seen that the wedging action of the bevelled points has broken the first two of the metal sections tying the halves of the shank together, the remaining unbroken metal sections preventing bulging of that portion of the shank which has not as yet passed through the outer sheathing 3.

When my improved fastening device is fully driven as illustrated in Figure 3 the bevelled points 6 cause the sections of the shank to diverge on arcuate paths, the severed metal sections forming barbs 7' firmly embedded in the material of the inner sheathing 4 thus obtaining a firm anchorage for the head to retain the outer sheathing in intimate contact with the inner sheathing.

30 In the modification illustrated in Figs. 4 to 8, I have employed the same principles as heretofore described in connection with Figures 1 to 3. In this modification however, I use a tubular shank with the perforations 5 arranged to produce four lines of weakness and insert a wedge 8 clearly seen in Figure 5 between the bevelled edges 6 of the prongs. This wedge has a point which centers the wedge and maintains, in conjunction with the cylindrical portion 10 lying 40 within the tubular shank of the fastening device, a short straight path of penetration of the wedge into the inner sheathing. In this case the sloping surface 11 of the wedge starts and insures the equal severance of the thin metallic portions 7 which until they pass through the outer sheathing prevent the buckling of the segments of the shank.

45 In this modification I have also added the barbs 12 which are pressed into the material of the inner sheathing and together with the barbs 7' insure that the anchorage is even greater than that due to the additional number of prongs. Likewise in the manufacture of the type illustrated in Figures 4 to 8 thinner material may be used for the shank with the result

that the four prongs with their barbs may penetrate the inner sheathing with less destruction of the fibrous or granular structure, the barbs on the top and each side of each section of the shank insuring a firm anchorage with a holding power equal to the strength of the inner sheathing over the area covered by the locus of the points of the tips of the shanks.

It is, of course, to be understood that the foregoing are merely illustrative of my invention and that modifications may be made therein without departing from the spirit of the appended claim. One such obvious modification is that the angles of the ends and of the intermediate planes of the shanks and the comparative thicknesses of the weakened bending points will be proportioned for the various degrees of resistance of materials and of the holding power required.

Having thus described my invention what I claim is:

A fastening device adapted to be driven having a head and shank; the latter having a plurality of points tapered downwardly and outwardly from the axis of the shank and adapted to diverge as the fastening device is driven and a series of perforations through the shank spaced so as to leave frangible portions of said shank between said perforations, whereby said frangible portions prevent buckling of the unembedded portion of said shank and are broken by tension developed by the tapered points said tapered points bending the several severed sections of said shank outwardly during the driving operation.

OSCAR VATET.
